UNITED STATES PATENT OFFICE.

FRANK WAIDA, OF CHICAGO, ILLINOIS, ASSIGNOR TO MARY A. WAIDA, OF CHICAGO, ILLINOIS.

CANDY-MAKING MACHINE.

Application filed March 16, 1921. Serial No. 452,711.

To all whom it may concern:

Be it known that I, FRANK WAIDA, a citizen of the United States, residing at Chicago, Illinois, have invented certain new and useful Improvements in Candy-Making Machines, of which the following is a specification.

This invention relates to improvements in candy making machines and particularly to so called mint presses.

It is an object of the invention to provide a machine by which pieces of candy while in somewhat plastic condition may be compressed to uniform regular disk or "mint" size.

It is also an object of the invention to provide a machine of this character with means for flattening and finishing the lateral surfaces of the mint or candy to improve thereby the appearance of the finished article, as compared with those machines in which the sides are not smoothened.

The invention also has the object of automatically discharging the completed articles and to prevent the entrance of unsuitable pieces of material into the machine.

It is also an object of the invention to prevent the candy from sticking to the parts of the machine, and to facilitate the removal of the articles from the machine by periodically vibrating or striking a blow against the compartment in which the treatment is carried out.

With these and other numerous objects in view an embodiment of the invention is described in the following specification in which reference is made to the accompanying drawings:

In the drawings:

Fig. 1 is a top plan view of the machine;

Fig. 2 is a fragmentary top plan view showing certain parts in different positions;

Fig. 3 is a transverse sectional view through the machine on line 3—3 of Fig. 1;

Fig. 4 is an end view of the machine, and

Figs. 5 and 6 are elevational views in a different scale of a piece of candy, shown before and after treatment, respectively.

A casing 1, preferably rectangular in shape, is open on the top and is provided with a movable bottom 2. It is supported by the legs 3 and it is subdivided by stationary longitudinal walls 4, into several large compartments, two being shown in the embodiment illustrated, although the number of

these longitudinal compartments 5 may be increased as desired. These compartments again are subdivided by a plurality of stationary transverse partition walls 6 to form in each compartment a relatively large number of chambers 7. The chambers 7, which are shown to be fixed relatively to the casing, serve for receiving movable abutments, plungers or compression elements 8 which cooperate with the stationary abutments or transverse partition walls 6 to compress pieces P of candy while the latter is in plastic condition, and to convert the same into the ordinary form of mint, shown at M in Fig. 6.

A plurality of the movable partition walls or abutments 8 are interconnected by longitudinal members 9 which are slidably disposed within the compartments 5, these members being guided through cut-out portions 10 at the ends of the transverse partition walls 6; these longitudinal connecting members are shown in Figs. 1 and 3 to be closely adjacent to the longitudinal walls of the compartments. The connecting members 9 for the movable abutments are, therefore, suitably guided on each side of the compartment, and owing to these guiding elements the movable abutments are permanently kept in alignment. The two longitudinal connecting members 9 in each of the compartments 5 of the casing are united by an outer wall 12, at each end of the slide thus formed. These walls 12 serve for supporting rods 13 which pass through suitable openings in the end walls of the casing. Nuts 14 at the ends of the rods serve for securing the same adjustably to the end walls 12. The rods 13 of each pair are united near their free ends by a transverse member 15 on which brackets 16 for rotatably supporting a roller 17 are mounted. This construction of the roller 17 with the supports for the same and the connection of these supports with the end walls 12 of the slide, is repeated on each end of the casing thereby forming a complete self-contained structure for all movable abutments and which is movable longitudinally of the casing when one roller 17 is pushed in one direction, and movable in the other direction when the other roller is actuated in the same way.

In order to effect the reciprocatory movement of the structure within the casing and to bring thereby the movable abutments 8

alternately into and out of operative position with respect to the stationary abutments 6, a pair of cam wheels are provided, one at each end of the machine. The cam wheels 5 or disks 20 and 21, respectively, are fixed to a shaft 22 which is rotatably supported in bearings 23 on one of the longitudinal walls of the casing 1. This shaft receives its drive from a pulley 24 or in some other suitable 10 way. Each of these disks 20 and 21 is provided on the inner face with an arcuate cam 25 which extends approximately in circumferential direction and which rises from the plane of the disk surface to a distance from 15 said surface, as indicated in Fig. 1. The cams 25 are preferably offset 180° with respect to each other, with the result that in each complete revolution of the shaft 22, one of these cams 25 will act upon the roller 17 at 20 one end of the casing alternatively with the action of the other cam 25 on the roller 17 at the other end. Owing to this intermittent alternative action upon the opposite 25 ends of the slide, the latter will be reciprocated in the interior of the casing, thereby moving the abutments 8 carried by the structure into and out of operative position with respect to the stationary abutments. In the 30 drawing shown in Fig. 1 the roller 17 at the right hand end of the casing is shown as being influenced by the cam 25 of the disk 20, thereby having moved the slide to the left. The movable abutment indicated at 8^x is 35 shown in operative position with respect to the stationary abutments 6^x, thereby compressing that piece of candy (not shown) which has been introduced into the space between these movable and stationary abutments prior to compression. In Fig. 2 the position 40 of these parts is shown slightly altered, the movable abutment member 8^x being now at a relatively large distance from the stationary abutments 6^x and permitting thereby a new piece of material of suitable size and of 45 the shape shown in Fig. 5, to drop into the space between the two abutments.

From Figs. 1 and 2 it will also be noted that the slide may be moved so as to bring the successively movable abutments 8 into 50 cooperation with different or opposite surfaces of the same stationary abutments 6. The abutment 8^x which first, as in Fig. 1, was at a relatively large distance from the abutment 6^y, is now so closely positioned to 55 the same that the candy may be compressed between these parts to approximately the shape shown in Fig. 6.

The bottom 2 of the casing is connected by hinges 26 to one of the longitudinal edges 60 of the side wall of the casing 1. In order to discharge the compressed material from the chambers in which it has been treated the bottom 2 is tilted and this tilting preferably coincides with the periods during which 65 the movable plungers 8 are out of operative

relation with the stationary abutments 6. This bottom 2 has a tendency to swing by its own weight into the position indicated in dotted lines in Fig. 3. It is, however, held normally in the position indicated in full 70 lines by means of a retaining bar 27 which is pivotally secured to a transverse rod 28 supported in bearings which preferably are secured to the legs 3 of the machine. This retaining bar 27 projects at one end of the 75 machine as shown in Fig. 1 at the right hand end, underneath a bar 29 which is fastened in a suitable way to the lower surface of the bottom wall 2 and which is extended beyond the end wall of the machine, so as to be engaged from below by the projecting latch-bar 27. The bar is permanently forced yielding into engagement with this part of the bottom 2 and for this purpose a collar 30, rigidly secured on the stationary rod 28, has 80 fixed thereto a spring 31, the other end of which is secured to a projecting hook or the like 32 on the bar 27, to hold the same normally in the position illustrated in Figure 3 and Figure 1. An extension 33, preferably integral with the bar 27, projects into the path of one or more eccentric pins 35 secured to the disk 20, and, according to Fig. 1, located on the outer face of the same. It will be seen, therefore, that during the rotation of the disk 20 and a predetermined period after the roller 17 has been moved to 90 actuate the slide structure into operative position, an eccentric pin 35 will engage the extension 33 of the bar 27, thereby forcing 95 this extension downwardly. The bottom 2 under its own weight, will then drop into the position indicated in dotted lines in Fig. 3, the projection 29 remaining in engagement with the latch-bar 27, whereby after the passage of the roller 35 over the end 33 of the bar 27, the latter is forcibly again drawn upwardly by the spring 30 under coaction of the weight 36 to arrive again in the position indicated in full lines. The disk 20, which 105 controls the movable abutments 8 therefore also effects in the present construction a discharge 110 of the treated material from the machine.

This discharge of treated articles is facilitated by the provision of a hammer or 115 the like which strikes a blow against a wall of the casing, so as to vibrate the same and to cause the removal of those objects which might otherwise have a tendency to adhere to the same. A hammer block 40 is fixed 120 to an oscillatable shaft 41, approximately midway of the length of the machine, and as shown in Fig. 3 is constructed as an angular member which normally by its own weight has a tendency to lean against the 125 adjacent wall of the casing or to strike the same. The rock shaft 41 which is also supported in bearings 42 projecting from the casing, is provided with an adjustable collar 43 on which a spring 44 is secured. The 130

other end of this spring is anchored to a fixed pin 45 or the like projecting from an end wall of the casing. If, therefore, a rocking movement is imparted to the shaft 41 in a direction in which the spring 44 is tensioned, the spring, upon release of the shaft, will return the latter forcibly into its previous position. As the shaft is weighted in the present instance, by the attachment of the hammer 40 to the same, the momentum of the parts will have a tendency to carry the shaft beyond the position it occupied at first, and a sharp blow will, therefore, be struck by the hammer under spring tension against the wall of the casing. The means controlling the operation of the compressing elements 8, in the present case the disk 21 also serves for imparting this movement to the rock shaft 41, and for this purpose this disk carries one or more eccentric projecting pins 46 which, in each revolution of the disk, intermittently engage an arm 47 fixed at one end to the rock shaft 41. When this arm is moved downwardly as indicated in Fig. 4, the spring 44 is tensioned, and upon the passage of the pin 46 over the end of the arm 47 the spring will forcibly throw the hammer 40 against the side wall, thereby releasing the finished articles which otherwise might have stuck thereto.

Means are also provided to prevent the entrance into the various compressing chambers of pieces of excessive size or to prevent that chunks of candy consisting of two or more of the knobs P should enter the same compartment or should remain suspended on the top edge of one or more movable or immovable abutments.

For this purpose a plurality of obstructions are placed into the path of the articles and these obstructions are arranged with respect to the chambers in which the candy is compressed in such manner that the candy if of proper size will be deflected into one of the chambers or if of excessive size will be prevented from coming into contact with an edge of any chamber.

A plurality of fingers 60 is mounted on each of two rock shafts 61, which are supported in bearing lugs 62 on the walls of the casing. These fingers, which may be of stiff wire or the like, project from these rock shafts over the top of the machine, and as indicated in Figs. 1 and 2 are each adapted to oscillate in a vertical plane which is somewhat close to the stationary abutments 6 of the casing. The articles of the proper size, therefore, may drop on each side of the abutment 8, but if there should be two of the knobs P not completely cut through by the stick cutting machine (which is not shown in the drawing), this set of interconnected knobs P will be caught by these projecting fingers and will be prevented from

dropping into any of the chambers or even from contacting the edges of the same. These fingers 60 project from each side towards the center plane of the machine and are located somewhat offset to each other. This arrangement corresponds with the location of the stationary abutments 6 against which the candy mass is compressed, and they, therefore, effectively prevent the entrance of pieces of excessive size or of a set of interconnected knobs P. They aid, however, in deflecting pieces of proper size to one side or the other, thereby distributing the articles uniformly. Masses of excessive size will be caught by the fingers, which serve for eliminating these pieces from the path of other pieces fed into the machine, the elimination being due to a swinging movement of the fingers.

This again is produced by rocking the shafts 61 on which the fingers 60 are mounted. The shaft 22 is provided with a cam 63, projecting intermittently against a hook-shaped cam 64 which is located on the end of one of these rock shafts 61. During the rotation of the main shaft 22, therefore, the cam 63 intermittently strikes the hook on the rock shaft and swings the same. This rock shaft is also equipped with a finger 65 projecting from the shaft near one end wall of the casing 1 in approximately horizontal direction. The front end of this finger is provided with a hook 66 or the like. Another finger 67 also projects in a similar way from on the other rock shaft in opposite direction. The second finger overlies the first described finger and if, therefore, in the operation of the machine the finger 65 is lifted, it will also lift the finger 67 and thereby cause the rocking movement of the second shaft 61. While, therefore, one of the sets of the obstructions is actuated directly by the drive shaft 22 of the machine through the provision of suitable cams, 63, 64, this first set is in engagement with a controlling element of the second set of obstructions and causes operation of the latter.

After the passage of the cam 63 over the hook 64 the rock shafts 61 which are freely oscillatable have a tendency to swing back by gravity into the previous position and this return movement is facilitated by a weighted arm 68 which is connected with the second rock shaft. This arm preferably is at that end of the rock shaft which is opposite the arm 67. This rock shaft being forcibly returned owing to the weight 68 and having a finger 67 which overlies the other arm 66 will, therefore, induce a return movement of the first mentioned rock shaft. The latter will again drop into the position indicated in Fig. 4, in which the arm 66 strikes a stop 70 which is secured to the end wall of the casing.

From the above, the operation of the ma-

chine will be understood. The masses of candy which are cut from a semi-plastic stick, preferably of annular cross-section, and which have the shape indicated in Fig. 5, are dropped through a suitable chute, not shown, which feeds these candies into the casing 1. These chutes which may extend from the candy cutting mechanism and which are not illustrated, may terminate a short distance above each of the compartments; they serve for directing the severed pieces into the same. Those abutments 8 which are remote from the stationary abutments 6 permit these short cylinders P to enter between two abutments while other pieces of candy which are wider, will be held up by the obstruction fingers 60 and will remain, therefore, suspended on these fingers above the top edge of the casing. In the rotation of the disks 20, 21 produced in some suitable way, the cams 25 will alternately act on the rollers 17, and thereby shift the movable abutments 8 of the various individual pressure chambers to compress the candy to the mint form, as indicated at M in Fig. 6. In the continued rotation the cam or eccentric pin 35 will strike against the extension 33 on the bar 27, which is forcibly held upwardly and which holds the bottom 2 in closed position. Upon the forced descent of this extension 33 the bottom will drop by gravity and the compressed candy will be discharged from the various compartments or chambers, the more so as this release of the bottom occurs after the movable abutments 8 are not influenced any more by the cam 25. This discharge of the compressed candy is furthermore facilitated by the vibration which is imparted to the casing through the hammer 40, this hammer being under the control of the pins 46, acting in rapid succession on the arm 47, which is connected to the rock shaft 41 of the hammer. The hammer itself is moved under spring pressure against the end wall of the casing, the pins 46 merely serving the object of tensioning the spring 44 and raising the hammer to a distance from the side wall of the casing. The fingers 60, which serve as obstruction elements to prevent the entrance of pieces of excessive size into the compression chambers and which, thereby, eliminate that interference which might be produced by these pieces in the operation of the machine, are then moved, owing to the engagement of the hook 64 by the cam 63 and these excessive pieces which have not undergone any compression are thrown out of the machine and may either be cut up immediately so as to make possible their proper passage through the machine, or if they cannot be treated in this machine and form waste products of sufficient value they can be sold cheaper, or may be boiled again in a new batch of candy.

I claim:

1. In a machine of the character described, the combination of a casing, a plurality of compression members movable within said casing, means for actuating said compression members, and means for producing an intermittent vibration of wall portions of said casing. 70
2. In a machine of the character described, the combination of a casing, a plurality of compression members movable within said casing, means for moving said compression members intermittently in a predetermined direction and means for intermittently producing a vibration of wall portions of the 75 casing. 80
3. In a machine of the character described, the combination of a casing, compression members within said casing, means for intermittently reciprocating said compression members, a hammer, and means associated with the first named means for forcibly moving intermittently the hammer against a wall of the casing. 85
4. In a machine of the character described, the combination of a casing, movable compression members within the casing, means for actuating said compression members, and means associated therewith for intermittently setting up vibration of wall portions of the 90 casing, subsequent to each actuation of said compression members. 95
5. In a machine of the character described, the combination of a casing, compression members within the casing, means for reciprocating said compression members, a spring controlled hammer, and means under the control of the means which actuate the compression members for alternately tensioning the spring of the hammer and releasing the 100 same. 105
6. In a machine of the character described, the combination of a casing, compression members therein, a rotary cam disk and means under control of the cam for reciprocating said compression members, a rock shaft, a hammer block mounted on said rock shaft and normally leaning against the wall of the casing, a spring for yieldingly retaining the hammer in said position, and means 110 under control of the cam disk for alternately tensioning and releasing the spring to cause the hammer to strike blows against the wall of the casing. 115
7. In a machine of the character described, the combination of a casing, a plurality of compression members movable within the casing, a cam disk actuating said compression members, a rock shaft supported by the 120 casing, a hammer secured to said rock shaft, 125 a spring associated with said rock shaft and casing for normally forcing said hammer against the wall of the casing, an arm on said rock shaft and an eccentric pin on the cam disk adapted to actuate said arm to 130

- rock the shaft and tension the spring, said spring upon release being adapted to forcibly move the hammer in direction towards the wall of the casing.
- 5 8. In a machine of the character described, the combination of a casing, a plurality of compression members movable therein, means for actuating said compression members, a hammer, means under control of the compression member actuating means for removing the hammer from the casing, and means for forcibly returning the hammer against said casing.
- 10 9. In a machine of the character described, the combination of a casing divided into a plurality of compression chambers, compression members movable within the casing, means for actuating these compression members, obstructing elements overlying said compression chambers and adapted to prevent the entry of pieces of excessive size into said chambers, and means for swinging said obstruction elements in opposite directions.
- 15 10. In a machine of the character described, the combination of a casing divided into a plurality of compression chambers, compression members movable within the casing, means for actuating said compression members, a rock shaft, obstructing elements secured to said rock shaft, and overlying said compression chambers, and means for intermittently actuating said rock shaft.
- 20 11. In a machine of the character described, the combination of a casing divided into a plurality of compression chambers, compression members movable within the casing, a rotary shaft, means under control of the shaft for actuating said compression members, a plurality of obstruction elements overlying the compression chambers and adapted to prevent the entry of pieces of excessive size into said compression chambers, and means controlled by the shaft for actuating said obstruction elements.
- 25 12. In a machine of the character described, the combination of a casing divided into a plurality of compression chambers, compression members movable therein, obstruction elements overlying said compression chambers and adapted to prevent the entry of pieces of excessive size into said chambers, and common, rotary means from which actuation of said compression members and obstructing elements is controlled.
- 30 13. In a machine of the character described, the combination of a casing divided into a plurality of chambers, compression members movable within said casing, obstruction elements overlying said chambers and adapted to retain pieces of excessive size in a plane above said chambers, means for controlling the actuation of said members and means for actuating said obstructing elements, to remove the pieces retained
- 35 by said obstruction elements from their position above the casing.
- 40 14. In a machine of the character described, the combination of a casing divided into a plurality of chambers, compression members movable within said chambers, tiltable obstructing elements overlying said chambers, and adapted to prevent the entry of pieces of excessive size into the same, and a common shaft controlling the reciprocating movement of said compression members and the tilting movement of said obstruction elements.
- 45 15. In a machine of the character described, the combination of a casing divided into a plurality of chambers, compression members movable within the casing, obstruction elements overlying said compression chambers, and a common shaft for controlling rectilinear movement of said compression members and successive tilting movement of said obstruction elements.
- 50 16. In a machine of the character described, the combination of a casing, having several series of compression chambers, compression members movable within said chambers, means for actuating said compression members, a plurality of series of obstructing elements, corresponding with the number of series of compression chambers, means for simultaneously actuating said compression members in all series, and means for simultaneously actuating the obstructing elements in all series.
- 55 17. In a machine of the character described, the combination of a casing, a plurality of compression chambers in said casing, obstruction elements arranged in several series above the compression chambers of the casing, means for positively actuating one of said series and means connected with said actuated series for causing actuation of a second series of obstructing elements.
- 60 18. In a machine of the character described, the combination of a casing, a plurality of compression chambers therein, obstruction elements above the chambers, positively acting means for actuating certain of said obstruction elements, and means associated with said certain obstruction elements for actuating certain other obstruction elements.
- 65 19. In a machine of the character described, the combination of a casing having a plurality of compression chambers, obstruction elements associated with said chambers, positively controlled means for moving obstruction elements in a predetermined direction, and gravity controlled means for returning said obstruction elements to their first position.
- 70 20. In a machine of the character described, the combination of a casing divided into a plurality of compression chambers, 75
- 75
- 80
- 85
- 90
- 95
- 100
- 105
- 110
- 115
- 120
- 125
- 130

compression members movable within said casing, means for actuating said compression members, a bottom to said casing, means for normally retaining said bottom in closed position, positively acting means for permitting the bottom to open, a hammer, means for striking said hammer against a wall of the casing, obstruction elements overlying said chambers, means for actua-

ting said obstruction elements to remove 10 pieces retained thereby from their position above the casing, a shaft, said actuating means for the compression elements, release means for the bottom, and actuating means for the obstruction elements, being con- 15 trolled by the same shaft.

In witness whereof I affix my signature.
FRANK WAIDA.
